PACKAGING TRAY FOR FOOD OR THE LIKE

Gail Rogers, 538 N. Louise, Apt. 5, Glendale Calif. 91206; Billy Spiedel, 11137 Densmore Ave., Granada Hills, Calif. 91345; Edward Briskin, 2213 El Baile Place, Hacienda Heights, Calif. 91745; and Peter Rodgers, 12424 Texas Ave., Apt. 1, Los Angeles, Calif. 90025

Filed Feb. 20, 1975, Ser. No. 551,473

Term of patent 14 years

Int. Cl. D9—03

U.S. Cl. D9—187

FIG. 1 is a top perspective view of a packaging tray for food or the like showing our new design, the side and end not shown being the same in appearance as the respective side and end shown;

FIG. 2 is a top plan view;

FIG. 3 is a bottom plan view;

FIG. 4 is an end elevational view; and

FIG. 5 is a sectional view taken on the line 5—5 of FIG. 2.

We claim:

The ornamental design for a packaging tray for food or the like, as shown and described.
